UNITED STATES PATENT OFFICE.

JOSEPH B. SARGENT, OF NEW HAVEN, CONNECTICUT, ASSIGNOR TO
SARGENT & CO., OF SAME PLACE.

DESIGN FOR ORNAMENTATION OF HINGES.

SPECIFICATION forming part of Design No. 13,546, dated January 23, 1883.

Application filed November 27, 1882. Term of patent 14 years.

To all whom it may concern:

Be it known that I, JOSEPH B. SARGENT, of New Haven, in the county of New Haven and State of Connecticut, have invented a new 5 Design for the Ornamentation of Butt-Hinges; and I do hereby declare the following, when taken in connection with accompanying drawings and the letters of reference marked thereon, to be a full, clear, and exact description 10 of the same, and which said drawings constitute part of this specification, and represent, in—

Figure 1, a face view; Fig. 2, a rear view.

This invention relates to a design for the 15 ornamentation of butt-hinges; and it consists in the ornamentation as shown in the accompanying illustration and hereinafter described.

The face of the hinge shows a plain border around its margin. Transversely across the 20 face of the central portion of this surface from the outside is a series of bars, *a*, leaving a sunken space between the said bars. Between these bars and each end is a sunken panel, into each of which a screw-hole cuts, 25 and springing from that part of the screw-hole in the panels is a series of radial points extending onto the surface. Above and below the panels is a series of raised ornaments; but these may be omitted, the essential feature 30 of this part of the design being the transverse bars with the radial points around the screw-holes, as shown. The ground of the surface may be plain, reeded, or otherwise roughened. The ornamentation of the back

of the hinge consists of a vertical sunken 35 panel in the exposed surface of that side of the hinge, with radially-projecting points springing from one of the vertical sides onto the face of the panel, as shown in the accompanying illustration.

While the ornamentation herein shown and described is intended to be used for the two sides of the hinge, the surface of either side may be differently ornamented, the other side retaining the ornamentation herein described. 45 I therefore do not wish to be understood as limiting my invention to a design for the two faces combined; but

I claim—

1. The design for the ornamentation of the 50 face of a butt-hinge, consisting of the margin around the edge of the part, transverse bars on the central portion extending from side to side, with the panel above and below, on which is a series of points springing from one side of 55 the said panels onto the surface thereof, substantially as described, and shown in the accompanying illustration.

2. The design for the ornamentation of butt-hinges, consisting of a sunken panel on the 60 reverse surface, with radial points springing from one side onto the surface of the panel, as described, and shown in the accompanying illustration.

JOSEPH B. SARGENT.
